UNITED STATES PATENT OFFICE

2,219,693

WATER COOLED FURNACE DOOR

Edward J. McDonnell, Fox Chapel, Pa., assignor
to Blaw-Knox Company, Pittsburgh, Pa., a cor-
poration of New Jersey

Application May 9, 1939, Serial No. 272,605

9 Claims. (Cl. 122—498)

This invention relates to water cooled furnace doors such as are used in open hearth furnaces.

The doors used on open hearth furnaces must withstand very severe treatment. They are subjected on their inner faces to extremely high temperatures. They must be strong enough to withstand the various blows and stresses to which they are subjected in service. Furnace doors were originally made of cast metal and water cooling was resorted to at a very early date. For example, in McDonald Patent 258,095, dated May 16, 1882, there is shown a water pipe cast in a door frame. Such doors, however, are wholly unsuited to present day requirements. Since that time a very large number of door constructions have been devised. Doors have been made with hollow bodies and hollow rails (Knox Patent 789,550, dated May 9, 1905). Wrought metal welded to form has been used in place of cast metal (Knox Patent 1,037,778, dated September 3, 1912). Others have been made with openings through the body portion for the purpose of better tying in the refractory lining of the door to the metallic portions thereof (Williams Reissue Patent 17,864, November 11, 1930). Experience has shown, however, that all of these doors have practical shortcomings. One of the principal difficulties encountered, despite the water cooling which has been provided, is distortion of the door after continued use. Such distortion makes for a leaky door opening and may result in loosening of the refractory lining. The conditions of service are so severe that maintenance, both from the standpoint of cost and inconvenience, becomes an important factor.

I have observed that one of the most vulnerable parts of a door from the standpoint of maintenance is the lower ridge or rail. The doors on an open hearth furnace are in closed position most of the time—probably 95% of the time—and when closed the only metallic portion which is exposed directly to the heat of the furnace is the lower rail. While attempts have been made to cool the bottom rail by supplying the cooling water to it in the first instance (see Knox Patent 1,037,778, above referred to), the difficulty has not heretofore been overcome. There has been a tendency to deposit dirt or sludge in the bottom of the door, either at the bottom of the body portion or in the lower rail, thus decreasing the cooling effect and increasing the likelihood of distortion. The lack of positive circulation through the exposed rail also is likely to result in such a rise in water temperature as to cause deterioration of the metal from acid-

ity in the water or from other entrained substances.

My improved door is designed to overcome or minimize these difficulties.

In the accompanying drawing illustrating a present preferred embodiment of the invention and certain modifications thereof,

Fig. 1 is an elevation of my improved door as viewed from the back or exterior side;

Fig. 2 is an elevation of the door as viewed from the front, that is to say, the furnace side;

Fig. 3 is a bottom view;

Fig. 4 is a vertical section on the line IV—IV of Fig. 1;

Fig. 5 is a view corresponding to a portion of Fig. 1 but showing a modified structure, and

Fig. 6 is a vertical section through the bottom portion of a still further modification.

Referring first to Figs. 1 to 4 inclusive, the door is shown as being made of wrought metal plates bent and welded to form a body 2 with integral side rails 3 and 4 and a top rail 5. The front plate 6 and the back plate 7 of the body are tied together by stays 8 and are both pierced and turned inwardly to form the customary peep hole 9. Hangers 10 are secured to the top rail 5 for hanging the door on the door lifting mechanism, and an eye 11 is provided to receive a crane hook or sling for use in mounting the door or moving it about.

Within the door there is provided a partition 12 which forms a water tight barrier between the rail 4 and the water space of the door. A water connection 13 is provided at the top of the door and in the preferred use of my invention this connection will serve as the inlet for the cooling water. Cooling water thus supplied travels downwardly along the rail 4 to the bottom of the door and passes thence through a conduit 14 extending across the bottom of the door between the rails 3 and 4. This conduit, as illustrated in Figs. 2 and 3, is a length of heavy pipe whose ends are welded into the rails 3 and 4, as indicated at 15. The cooling water passes through the pipe 14 and is discharged through an elbow 16 into the rail 3. It circulates through the remaining water space of the door and is taken off through a water connection 17.

The pipe 14 is of relatively small cross section as compared with the other passages through which the water must flow between the connections 13 and 17. In consequence the water travels through the pipe at relatively high velocity. This increases the cooling effect and minimizes

the danger of deposits tending to clog the system. It is an unfortunate fact that in practice furnace doors are not kept as free of deposited dirt or sludge as they should be, and in doors of usual construction this is likely to cause a burning out or cracking of the exposed water cooled surfaces. In my design the neglect of such cleaning out is of little consequence. Such sediment as may be deposited will lodge in the bottom portion 18 of the body, where it is subjected to relatively little heat from the furnace because this portion lies behind the pipe 14. Wash-out plugs 19 are provided for removal of this deposit.

It will be noted that the provision of a conduit 15 of relatively small cross section insures adequate cooling in two ways. First, the velocity of the cooling water is substantially increased, and second, the area of metal exposed to the furnace heat is substantially reduced.

By reason of the facts above stated, there is very little likelihood of trouble with my improved door, but if the door should be abused and damaged it is a very simple matter to remove the pipe 14 and weld a new one into place. This will, in all likelihood, be the only repair necessary, because even under conditions of extreme abuse, distortion of the pipe 14 from excessive heat will not lead to distortion of the remainder of the door.

The elbow 16 prevents accumulation of dirt at the bottom of the rail 3 in such manner as to insure against plugging at the end of the conduit 14.

The door is provided with a refractory lining 20. Usually this lining will be built up of brick-work as shown. The rails 3, 4 and 5 are all beveled inwardly so as to help hold the brick-work in place. The brick-work is supported in part by the pipe 14 and in part by ledges 21 which are welded to the front plate 6. If desired, these ledges can be placed at a somewhat lower level than the pipe 14 so as to give the effect of an inward bevel and thus help to key the brick-work in place.

A reinforcing plate 22 is provided around the bottom portion 18 of the door. This reinforcement consists of an angle-shaped guard piece which extends across the back of the door body through the bottom and also extends beneath the bottom. This reinforces the door against blows from the charging machine and compensates in this respect for the removal of the bottom rail ordinarily employed. It has heretofore been deemed desirable to maintain the door at full thickness at the bottom in order to give the door adequate strength against blows from the charging machine. My improved door thus departs markedly from usual construction.

It will be noted from Fig. 4 that the pipe 14 is placed above the plane of the bottom of the door. It is thus adequately protected against being struck by the charging boxes or scrap therein during the charging of the furnace.

Various modifications may be made. For instance, instead of welding the conduit 14 into place, it may be provided with threaded connections. Generally speaking, however, I prefer to use a welded connection.

As above indicated, I prefer that the cooling water shall be fed through the rail 4 so as to pass through the pipe 14 before circulating through the rest of the door. If desired, however, this may be reversed. In either case the high speed circulation through the pipe 14 will be attained,

but in the latter case it will enter the pipe somewhat warmer.

In Fig. 5 I have shown a modified door wherein the partition 12 is omitted and the water connection 13' leads to a pipe 30 extending downwardly inside the rail 4' and connects to an elbow 31 to the pipe 14'.

In Fig. 6 I have illustrated another modification in which a partition 40 is provided so as to form a conduit 41 at the bottom of the door on 10 the furnace side. In this case the conduit 41 will be arranged in the circulatory system in the same fashion as the pipe 14 or 14'.

My improved door has numerous advantages. It is not unduly expensive to construct and requires a minimum of maintenance. All of the cooling water supplied to the door passes at high velocity through the bottom portion which is exposed to the flame, thus doing away with the dangers of distortion and deterioration from attack of acids or deposition of dirt.

While I have illustrated and described the present preferred embodiment of my invention and various modifications thereof, it will be understood that this is by way of example only, 25 and that the invention may be otherwise embodied and practiced within the scope of the following claims.

I claim:

1. A water cooled furnace door comprising a 30 hollow body, hollow top and side rails projecting from one side of the body to form an open-faced and open-bottomed recess for a refractory lining, and a conduit extending across the bottom of the recess in front of the body and between the side rails and forming a water space 35 separate from the body, the conduit being of relatively small cross section as compared with other water passages in the door.

2. A water cooled furnace door comprising a 40 hollow body having hollow top and side rails projecting from one side thereof to form an open-faced recess for a refractory lining, and a water conduit extending across the bottom of the recess in front of the bottom portion of the hollow body but forming a separate water space 45 across the width of the door, the ends of the conduit making connection with the inner faces of the side rails.

3. A water cooled furnace door comprising a 50 hollow body, hollow top and side rails projecting from one side of the body to form an open-faced and open-bottomed recess for containing a refractory lining, a water conduit of relatively small cross-section separate from the body extending across the bottom of the recess, and a supporting ledge on the body for supporting a refractory lining.

4. A water cooled furnace door comprising a hollow body, hollow top and side rails projecting 60 from one side of the body to form an open-faced and open-bottomed recess, a refractory lining in the recess, a conduit separate from the body extending across the bottom of the recess in front of the body and between the side rails, 65 and a supporting ledge on the body upon which the refractory lining may rest.

5. A water cooled furnace door comprising a hollow body, hollow top and side rails projecting from one side of the body to form an open-faced and open-bottomed recess for a refractory door lining, a water conduit separate from the body extending across the bottom of the recess in front of the body and between the side rails, 70 and a reinforcement for the bottom of the body. 75

6. A water-cooled furnace door comprising a body made from two rectangular metal plates spaced apart to provide a water space therebetween, a hollow top rail and two hollow vertical side rails each of generally rectangular section and extending around three sides of the periphery of the door, the rails extending inwardly so as to form an open-faced and open-bottomed recess for containing a refractory lining, and a water pipe of generally circular cross-section extending across the bottom of the recess in front of the body and terminating in the two side rails, the pipe being adapted to support the refractory lining within the recess, and water connections for supplying cooling water to the pipe and thence to the interior of the door.

7. A water-cooled furnace door comprising a body made from two rectangular metal plates spaced apart to provide a water space therebetween, a hollow top rail and two hollow vertical side rails each of generally rectangular section and extending around three sides of the periphery of the door, the rails extending inwardly so as to form an open-faced and open-bottomed recess for containing a refractory lining, and a water pipe of generally circular cross-section extending across the bottom of the recess in front of the body and terminating in the two side rails, the pipe being adapted to support the refractory lining within the recess, and water connections

for supplying cooling water to the pipe and thence to the interior of the door, the pipe being of smaller cross-section than any of the rails.

8. A water-cooled furnace door comprising a hollow metal body having hollow side rails extending outwardly from one face thereof so as to form a recess for a refractory lining, a pipe extending between the side rails and terminating therein, the bottom of the pipe being at a higher level than the bottom of at least one of the rails, the pipe being of smaller cross-section than said rail, and means for supplying cooling water first through the pipe and then through the said rail whereby foreign matter is substantially precluded from settling in the pipe.

9. A water-cooled furnace door comprising a hollow metal body having hollow side rails extending outwardly from one face thereof so as to form a recess for a refractory lining, a pipe extending between the side rails and terminating therein, the bottom of the pipe being at a higher level than the bottom of at least one of the rails, the pipe being of smaller cross-section than said rails, means for supplying cooling water first through the pipe and then through the said rail whereby foreign matter is substantially precluded from settling in the pipe, and a wash-out plug in said side rail near the bottom thereof and adjacent the outlet from the pipe into the side rail.

EDWARD J. McDONNELL. 30
